CHILD'S COSTUMER

Irmie Ann Gross, New York, N. Y.

Application June 23, 1955, Serial No. 36,646

Term of patent 3½ years

(Cl. D33—8)

The opposite side of the child's costumer is identical in appearance to the side shown in Figure 1.

I claim:

The ornamental design for a child's costumer, substantially as shown and described.
